COSMETIC APPLICATOR

Charles A. Mureau, Los Angeles, Calif.

Application August 14, 1939, Serial No. 289,953

1 Claim. (Cl. 15—137)

This invention relates to a device for facilitating the application of cosmetics and relates more particularly to a device for containing and applying paste lip rouge, mascara, and the like. A general object of this invention is to provide a compact and convenient device of the character referred to for containing two cosmetics of different shades or characters, and embodying novel means for facilitating the application of the cosmetics.

Another object of this invention is to provide a cosmetic applicator adapted to be carried in a pocketbook, or the like, and embodying two separate reservoirs for containing cosmetics, two brushes for applying the cosmetics, and simple, effective means for ejecting the cosmetics from the reservoirs to their respective brushes for application thereby.

Another object of this invention is to provide a device of the character referred to in which the cosmetic ejecting means are separately or individually operable.

Another object of this invention is to provide novel cosmetic ejecting means that are simple and inexpensive and yet effective and dependable.

Another object of this invention is to provide a device of the character mentioned in which replacement supplies of cosmetic may be easily supplied to the individual cosmetic chambers without removing the container or the heads of the container.

Another object of this invention is to provide a device of the character referred to in which the stems of the ejecting pistons are telescopically related in a novel manner to conserve space.

A further object of this invention is to provide a cosmetic applicator of the character referred to that is small and compact and shaped and proportioned to be conveniently handled and operated.

The various objects and features of my invention will be fully understood from the following detailed description of a typical preferred form and application of the invention, throughout which description reference is made to the accompanying drawing, in which:

Fig. 1 is a side elevation of the improved cosmetic applicator of the present invention showing one of the brush covers in longitudinal cross section. Fig. 2 is an enlarged fragmentary longitudinal detailed sectional view of the device showing certain parts in elevation. Fig. 3 is an enlarged transverse detailed sectional view taken as indicated by line 3—3 on Fig. 2, and Fig. 4

is a longitudinal sectional view of one of the brush means.

The device provided by this invention may be said to comprise, generally, a body 10, two cosmetic reservoirs or containers 11 arranged in the body 10 for independent turning, cosmetic applying means 12 on the containers 11, and means 13 for forcing or ejecting the cosmetic from the containers 11 to the means 12.

10 The body 10 is an elongate tubular member that carries the two cosmetic containers 11. The central longitudinal opening 14 of the body 10 is provided at its opposite ends with sockets 15 of enlarged diameter. The sockets 15 are of equal 15 depth and diameter and are cylindrical. An annular internal flange 16 is provided on the wall of the body opening 14 at the inner end of one of the sockets 15. The body 10 may be formed of any selected material and may be shaped, finished, and ornamented, as desired. In the case 20 illustrated the body 10 has a cylindrical external surface and is provided midway between its ends with a series of rings or beads 16a.

The containers 11 are provided to contain supplies of the cosmetics. The cosmetic containers 11 are hollow or tubular members having chambers or longitudinal openings 17 which serve as reservoirs for the cosmetics. In accordance with the invention the containers 11 may be alike or identical and are arranged to project from the opposite ends of the body 10. The inner portions of the containers 11 are shaped and proportioned to be rotatably received in the body sockets 15. Series of external annular beads 18 may be provided on the containers 11 to complement the body beads 16a. The beads 18 form or provide shoulders 19 which oppose or abut the opposite ends of the body 10. The outer portions of the containers 11 are formed to receive the applying 30 means 12. The outer end parts of the containers 11 are rounded or tapered and openings 20 of reduced diameter extend centrally through the reduced container parts to join the openings 17.

45 Novel means are provided to rotatably connect the containers 11 with the body 10. Annular grooves 21 are provided in the walls of the sockets 15 and annular grooves 22 are provided in the containers 11 to register with the grooves 21. The grooves 21 and 22 are flat-walled and are 50 preferably proportioned to form or provide annular spaces of square or rectangular cross section. Split spring rings 23 are arranged in the pairs of registering grooves 21 and 22 to hold the containers 11 against longitudinal movement relative to the body 10. The spring rings 23 are

square or rectangular in cross section to cooperate with the flat walls of the grooves 21 and 22. The grooves 22 in the containers 11 are sufficiently deep to fully receive the rings 23 when the rings are compressed. When assembling a container 11 in the body 10 a ring 23 is arranged in the groove 22 of the container and is compressed or contracted and the inner portion of the container is inserted in a body socket 15. When the container has reached its final position the ring 23 expands into the surrounding groove 21. The groove 21 limits the expansion of the spring ring 23 and holds the spring ring partially contracted so that its inner portion cooperates with the groove 22 in the container 11. It is preferred to connect the spring rings 23 with the containers 11 to turn with the containers. Each spring ring 23 has an inturned end part 24 received in a radial socket 25 in its respective container 11. The engagement of the parts 24 in the sockets 25 holds the rings 23 against turning relative to the containers. It will be seen that the containers 11 connected with the body 10 by the spring rings 23 are free to be independently turned relative to the body 10 and yet are dependably held against longitudinal movement and against displacement from the body.

The cosmetic applying means 12 are provided to facilitate the application of the cosmetics. An applying means 12 is provided on the outer end of each container 11. In the preferred form of the invention the means 12 are in the nature of brush means and the two means 12 are identical.

Each applying means 12 includes a tubular brush carrier 26. The carriers 26 have threaded cylindrical inner parts 27 adapted to be threaded in the openings 29 of the containers 11. The outer end parts of the carriers 26 are tapered to complement the tapered end portions of the containers 11. In the case illustrated the tapered outer parts of the carriers 26 have series of annular beads 28 similar to the beads 16^a and 18. The central longitudinal openings 29 of the tubular carriers 26 are longitudinally tapered throughout their major portions. In the preferred construction the inner end parts of the openings 29 are cylindrical and the openings taper from these cylindrical parts to the forward ends of the carriers 26.

The brush means 11 further include brush tufts 30 set or secured in the openings 29 of the carriers 26. The tufts 30 comprise groups of bristles arranged longitudinally in the openings 29 to project beyond the outer ends of the carriers 26. The inner portions of the brush bristles are fixed in the tapered openings 29. I prefer to set the inner parts of the bristles in a mixture of wax and rosin or a mixture of wax and synthetic wax that is sufficiently hard to dependably retain the bristles and yet will not crack or flake away. The wax and rosin mixture employed to set the brush tufts 30 is unaffected by the cosmetics and will not lose or free hard particles that may become mixed with the cosmetics.

The applying means 12 further include elongate shanks or tubes 31 arranged longitudinally in the set inner parts of the brush tufts 30. The tubes 31 are considerably smaller in diameter than the openings 29 to leave annular spaces for the set brush bristles. Openings 32 of large diameter extend through the tubes 31 to conduct the cosmetics from the openings 17 to the for-

ward portions of the brush tufts 30. It is preferred to relate the parts so that the forward ends of the tubes 31 are substantially flush with the forward ends of the carriers 26. The forward end parts of the tubes 31 are preferably tapered. I prefer to form the tubes 31 of metal and the forward parts of the tubes may be reduced or tapered by a spinning operation. Enlargements or flanges 33 are provided on the rear or inner ends of the tubes 31. The flanges 33 are pressed or force-fitted in the cylindrical inner parts of the openings 29. The flanges 33 thus secured in the openings 29 retain the tubes 31 in place and assist in securing the brush tufts 30 in the carriers.

In assembling an applying means 12 the brush tuft 30 is first set in the opening 29 and a heated pointed tool is then thrust through the wax and rosin mixture in which the bristles are set. The tube 31 is then arranged in the opening formed by the heated tool. It is to be noted that the brush tufts 30 are dependably retained by the wax and rosin mixture and by the wedging action of the tapered openings 29. The tubes 31 arranged longitudinally in the inner parts of the tufts 30 confine and assist in retaining the brush tufts. The beads 28 form effective grips by means of which the carriers 26 may be unthreaded from the openings 29. Thus the means 12 may be removed from the carriers 11 to allow the replenishing of the cosmetic supplies of the containers and to permit the replacement of the brush means 12.

Removable caps 34 are applied to the containers 11 to enclose and protect the brush tufts 30. The caps 34 are formed to be removably pressed on the projecting portions of the carriers 11. The sockets or openings 35 in the caps 34 receive the brush tufts 30 with clearance so that the caps do not distort the brush tufts. When the caps 34 are in place they prevent the cosmetics in the brush tufts 30 from soiling the clothing, hands, etc. The exteriors of the caps 34 may be suitably shaped, for example, they may be stepped or graduated in diameter, as illustrated.

The ejecting means 13 are separately or independently operable to force the cosmetics from the openings 17 into the brush tufts 30. There is an ejecting means 13 for each container 11. The ejecting means 13 each include a piston or plunger 36 operable in an opening 17. The plungers 36 have annular peripheral grooves 37 and split sealing elements 38 of rubber, leather, or the like, are set in the grooves 37 to slidably seal with the walls of the openings 17. The grooves 37 are of substantial depth to dependably retain the sealing elements 38. One plunger 36 is secured to the end of a tubular stem 39 while the other plunger 36 is fixed to the end of a stem 40 that may be solid. The stems 39 and 40 are telescopically arranged, that is, the stem 40 is received in the stem 39. As illustrated in Fig. 2 the stem 40 is received in the stem 39 with substantial clearance and does not cooperate with the stem 39. The tubular stem 39 has a thread 41 mating with a thread on the wall of the body opening 14. The thread 41 may extend throughout the length of the stem 39. The stem 40 has a thread 42 mating with a thread on the internal surface of the flange 16.

Means are provided to prevent relative rotation between the containers 11 and their respective plungers 36 whereby rotation of a container 11 relative to the body 10 threads or advances its plungers 36. These means comprise flat surfaces

43 on the walls of the openings 17. In practice there may be two diametrically opposite and substantially parallel surfaces 43 on the wall of each opening 17. The plungers 36 have flat peripheral surfaces 44 slidably engaging the surfaces 43. The engagement of the surfaces 44 with the surfaces 43 holds the plungers 36 and their respective stems 39 and 40 against rotation relative to the related containers 11 so that turning of the containers relative to the body 10 results in threading or advancement of the stems and plungers. The sealing elements 38 of the plungers 36 are cut away or provided with flat parts for sealing with the surfaces 43.

In the use or operation of the device of the invention the openings 17 may be loaded or provided with cosmetics before the carriers 26 are threaded in the openings 20. The plungers 36 are, of course, initially retracted. The openings 17 of the containers 11 may be provided with cosmetics of different kinds or of different shades or textures. The caps 34 are normally in place so that the device may be carried in a hand bag or the like without injuring the brush tufts 30 and without soiling the clothing, etc. When it is desired to apply one of the cosmetics the cap 34 is removed from one end of the device and the body 10 and the selected container 11 are turned one relative to the other. The body 10 and the container 11 may be conveniently grasped for this operation. Turning of the container 11 relative to the body 10 results in operation or advancement of the related plunger 36 and the plunger moving outwardly in the opening 17 ejects a portion of the cosmetic from the opening to the brush tuft 30. The cosmetic thus supplied

to the brush tuft 30 may be applied by means of the brush tuft. The body 10 and the associated containers 11 constitute an effective handle for the brush tuft to facilitate the application of the cosmetic. Following the application of the cosmetic the cap 34 is re-applied to the container 11. The supplies of the cosmetics may be readily replenished by merely retracting the plungers 36 to their initial positions and removing the carriers 26 to allow the cosmetics to be introduced to the openings 17. The carriers 26 are readily threaded from the openings 20. The device is small and compact and is adapted to contain adequate supplies of cosmetics.

Having described only a typical preferred form and application of my invention, I do not wish to be limited or restricted to the specific details herein set forth, but wish to reserve to myself any variations or modifications that may appear to those skilled in the art or fall within the scope of the following claim.

Having described my invention, I claim:

In a cosmetic applicator, a body adapted to be employed as a handle, a container for cosmetics entered in an end of the body to extend therefrom, a brush on the container for applying the cosmetics received therefrom, means retaining the container in the body for rotation and holding the container against longitudinal movement relative to the body, a plunger operable in the container, a stem on the plunger having threaded cooperation with the body, and means holding the stem against turning relative to the container whereby turning of the container relative to the body causes ejection of the cosmetics to the brush.

CHARLES A. MUREAU.
